HAT

Thelma Mae Di Pretoro, Washington, D. C.

Application February 18, 1955, Serial No. 34,573

Term of patent 14 years

(Cl. D3—13)

To all whom it may concern:

Be it known that I, Thelma Mae Di Pretoro, a citizen of the United States and a resident of Washington, D. C., have invented a new, original, and ornamental Design for a Hat, reference being had to the accompanying drawings, forming a part hereof.

Fig. 1 is a perspective view of a hat showing my new design;

Fig. 2 is a top plan view thereof; and

Fig. 3 is an enlarged sectional view of one of the eight ridged sections shown in Fig. 2.

The essential features of my design reside in the portions shown in solid lines on the drawing.

This application is a continuation-in-part of my application Ser. No. D. 29,992 filed April 14, 1954, and now abandoned.

I claim:

The ornamental design for a hat, as shown and described.
